UNITED STATES PATENT OFFICE.

HORACE LEONARD SHORT, ALBERT EUSTACE SHORT, AND HUGH OSWALD SHORT, OF BATTERSEA PARK, LONDON, ENGLAND.

AEROPLANE.

1,128,065.

Specification of Letters Patent.

Patented Feb. 9, 1915.

Application filed September 5, 1913. Serial No. 782,313.

To all whom it may concern:

Be it known that we, HORACE LEONARD SHORT, ALBERT EUSTACE SHORT, and HUGH OSWALD SHORT, aeronautical engineers, subjects of the King of Great Britain, all residing at 56 Prince of Wales' Mansions, Queen's Road, Battersea Park, in the county of London, England, have invented certain new and useful Improvements in or Connected with Aeroplanes, and of which the following is a specification.

This invention relates to aeroplane flying machines of the biplane type in which the wings can be folded rearwardly in order to reduce the span of the machine when it is not in flight.

The object of the present invention is to so construct the machine, that the upper and lower right hand wings and the upper and lower left hand wings, the inner ends of the rear spars of which are respectively hinged to a central stationary framework, are supported and guided near the termination of their rearward folding movements and so brought to their predetermined positions at the completion of said movements and are then engaged and carried by the central framework of the machine.

The invention is to further provide means for guiding the ends of the front spars of the folding portions of the wings into engagement with the central framework and for connecting and fixing the said ends of the said front spars thereto when the wings are in the flying position.

In conjunction with this invention a central stationary plane may be carried by the central framework to form a continuation of the upper planes of the right and left hand folding wing members when the latter are in their expanded and flying position. Also in some cases devices are provided by which the hinged wing portions may be turned about the said hinges from their flying to their folded positions, or vice versa, such devices being operable by the pilot while the machine is resting on the ground or floating on the water.

An example of construction of the invention is shown on the accompanying drawings which illustrate a biplane of the tractor type, in which the engine and propeller are arranged centrally on the fuselage.

Figure 1 is a side elevation of a hydro-aeroplane, showing the wings folded rear-

ward into a position parallel with the longitudinal axis of the machine. Fig. 2 is a plan view of the machine shown at Fig. 1, there being indicated also by dotted lines a portion of one of the wings when brought into position for flight. Fig. 3 is a front elevation on a somewhat larger scale of the machine shown at Fig. 1, with a portion of the main planes shown by dotted lines as when fully extended. Fig. 4 is a vertical section taken about the line X—X of Fig. 1, drawn to a larger scale than that figure, and illustrating means for the connection of the front upper and lower spars of the folding parts of the wings to the main stationary central part. Fig. 5 is a view similar to Fig. 4, but taken on the line Z—Z of Fig. 1, and illustrating the hinging of the rear upper and lower spars of the wings to the central portion of the structure. Fig. 6 is a vertical transverse section taken through the fuselage at about Y—Y Fig. 1, illustrating means for supporting the planes when folded against the fuselage, Fig. 7 being a plan view showing a certain forked support, and Fig. 8 showing a portion of one of the struts carrying collars hereafter referred to shown in section, and Fig. 9 is a side elevation of the struts carrying rollers.

As illustrated, the upper and lower right wings 1, and the upper and lower left wings 2 have the inner ends of the rear spars hinged to the framework of the machine, while the inner ends of the front spars are, when the machine is in position for flight, detachably fixed to the framework of the machine, so that by releasing the detachable fixtures of the front spars the wings can be turned back about the hinges of the upper and lower rear spars parallel with the fuselage.

Referring to Figs. 4 and 5, which further illustrate the central stationary framework before mentioned, there are arranged two front middle plane struts 3, 4 and two rear middle plane struts 5, 6 suitably braced together, and to which the fuselage 7 is fixed. At the upper ends these four struts carry a central upper fixed plane 8, Fig. 2, the front spar 9 of which may conveniently be formed tubular, see Fig. 4, while there is also carried between the upper ends of the rear middle plane struts 5 and 6 a rear upper center spar 10, and between the lower ends of the struts 5 and 6 there is carried a rear lower

center spar 10*, a front lower tubular strut 9* being carried between the lower ends of the front middle plane struts 3, 4. The central framework shown at Figs. 4 and 5 is braced together by wire stays as indicated. The inner ends of the rear spars 11 of the upper right and left wings 1, 2 are hinged to the ends of the rear upper center spar 10 of the struts 5 and 6, while the rear spars 11 of the lower right and left wings are hinged to the rear lower spar 10* of the struts 5 and 6. Any suitable construction of hinges may be employed for this purpose; the form illustrated primarily consists, as shown at Fig. 5, of two plates firmly bolted to the upper and lower surfaces of the spars 11 and connected by hinge pins 12 to extension members of the rear center spars 10, 10*, and through the heads of the pins 12 there are holes, to 20 which in one case are attached the back main flying wires 13, and in the other the main landing wires 14, see Fig. 5. It will thus be observed that the points, where the rear spars 11 of the upper and lower portions of the wings are hinged to the upper and lower center spars 10 and 10*, is such that when the wings 1, 2 are turned about the hinges described into the flying position indicated by the dotted lines at Fig. 2, the 25 inner ends of the upper hinged wings will conjoin the ends of the center fixed plane 8, while the inner ends of the lower hinged wings will abut against the lower part of the sides of the fuselage 7.

Since in a folding structure such as now described it is obvious that the weight of the hinged wings is liable to cause the position of the same to vary relatively to the central stationary framework when brought 30 from the folded to the expanded position and relatively also to the required position of rest when brought from the expanded to the folded position, it is highly necessary not only to provide means for connecting the 35 inner ends of the front spars of the wings to the stationary framework when brought to the expanded position, but it is also highly necessary to provide guiding means to facilitate the guiding of the said front spars into 40 proper alinement. Also it is equally necessary that when folded the wings should be supported and secured in such required position, and also that they should be guided and directed to such position of fixture. To 45 these ends the invention provides as follows. The inner ends of the front upper spars 15 and the inner ends of the front lower spars 16 of the hinged wings are fitted with projecting tapered pins 17 as shown at Fig. 4, 50 which tapered pins are adapted to enter the ends of the tubular front upper center spar 9 and the tubular front lower center spar 9* of the central stationary framework, which spars 9 and 9* are carried by the vertical struts 3 and 4. The upper pins 17 fit firmly

into the tubular front upper center spar 9 and are held in position by screw bolts such as 18, Fig. 4, passed through the tube and through the pins 17. The pins 17 are pointed to facilitate their entrance into the tubular ends of the spars 9 and 9*, and downwardly curved guides are provided on the ends of the front lower center spar 9*, with which guides the lower pins 17 contact as the wings are brought to their expanded positions, and thereby the pins are guided into their sockets in the tubular spars 9*, and consequently the pins 17 of the upper front spars 15 of the wings are also guided into their sockets in the center fixed frame. 55

When the wings are folded back parallel with and against the frame or fuselage they do not overlap each other but are brought into connection with the frame and so firmly held in position. Means are illustrated, particularly at Figs. 1 and 7 to 9, by which this is accomplished, such means consisting of forked supports 20 fixed to the fuselage 7, below which and also attached to the fuselage is a guiding fork 21, Figs. 6 and 9, the extremities of which are inclined. Fixed to the rear struts of the main plane are two rollers 23, Fig. 9, which when the planes are folded mount the guiding forks 21, while the struts 22 enter between the forks of the supports 20 and at this point, see Fig. 8, the struts are fitted with flanged collars 24. The rear portions of the main planes, when so folded back, are thus supported and relieve undue strain upon the hinges of the spars 11 described at Fig. 5. Thus when the folding planes are brought into the flying position, the connections of the upper and lower front spars are guided into engagement as described with reference to Fig. 4, and similarly when the wings are brought into their folding position the rear portions of the wings are again guided into their supports as at Figs. 7 to 9. 100

Wires or cables are connected to the wings 110 for the purpose of moving them from their folded position to their flying position, and vice versa, and such wires are led around suitable guiding pulleys or fair leads to winches. These winches are or may be 115 provided with any well known ratchet and pawl devices and, with brakes, for the purpose of preventing the movement of the wings except when substantial force is applied to operate the said winches. 120

In the construction illustrated in the drawings, at Figs. 1 and 2, two wire cables 125 are provided, one end of each cable being attached say at 26, Fig. 2, to the front spars 15 of the folding wings, and each cable extends respectively around pulleys 27, and thence by suitable guide pulleys 28, Figs. 1 and 2, to a ratchet winch 29, Fig. 1, placed in a convenient position to be operated by the pilot or his assistant. 130

In the drawings a second winch 30, Fig. 1, is provided for drawing the planes rearward when being folded, and to this winch 30 cables 31 are attached, respectively passing around pulleys underneath the fuselage, and so respectively to the rear parts of the folding wings to which the ends of the cables 31 are connected, as for example indicated at 32, Fig. 2.

10 Obviously to bring the folding wings from the position at Fig. 2 into the position for flight, the cables 25 must be wound up on the drums of the winch 29, while the cables 31 must be simultaneously unwound 15 from the drums of the winch 30.

When planes having a large chord are used and it is required to fold them in this manner, it is preferable to construct the rear portion of the wings so that they 20 hinge down in flaps immediately behind the rear spar, so that when the planes are folded back, they can be brought closer together than they otherwise would be. The total breadth across the two planes would, 25 when folded under these conditions, be somewhat less than double the chord of the plane.

The outer portion of the wings together with the struts and stays connecting the 30 upper and lower wings therefore swing on their hinges in the manner of gates and have an open position and a closed position. They are never adjusted in flight between these two positions, simply passing 35 from one position to the other according to which of the two positions is desired.

We claim as our invention.

1. In an aeroplane flying machine of the biplane type; the combination of a central 40 framework, upper and lower right hand wings and upper and lower left hand wings, hinged joints connecting the inner ends of the rear spars of the said right and left hand wings to the said central framework 45 to enable said right and left hand wings to be turned rearward from the flying position until they are about parallel with the central framework of the machine, means for guiding said wing members near the 50 termination of their rearward folding movements and supporting said wing members upon the central framework at the completion of said folding movement, and means for guiding to engagement and connecting the ends of the front spars of said folding wing members to the central framework when in their expanded and flying position.

2. In an aeroplane flying machine of the 55 biplane type; the combination of a central framework, upper and lower right hand wings and upper and lower left hand wings, hinged joints connecting the inner ends of the rear spars of the said right and left hand wings to the said central framework

to enable said right and left hand wings to be turned rearward from the flying position until they are about parallel with the central framework of the machine, means for guiding said wing members near the 70 termination of their rearward folding movements and supporting same upon the central framework at the completion of said folding movement, means for guiding to engagement and connecting the ends of the front spars of said folding wing members to the central framework when in their expanded and flying position, and a central stationary plane carried by said central framework to form a continuation of the 75 upper planes of the right and left hand folding wing members when in their expanded and flying position.

3. In an aeroplane flying machine of the biplane type; the combination of a central 80 framework, upper and lower right hand wings and upper and lower left hand wings, hinged joints connecting the inner ends of the rear spars of the said right and left hand wings to the said central framework 85 to enable said right and left hand wings to be turned rearward from the flying position until they are about parallel with the central framework of the machine, means for guiding said wing members near the 90 termination of their rearward folding movements and supporting said wing members upon the central framework at the completion of said folding movement, means for guiding to engagement and connecting the ends of the front spars of said folding wing members to the central framework when in their expanded and flying position, and means operable by the pilot on the machine to turn the hinged wing members about their hinges from their flying 95 position to their folded position while the machine is resting on the ground or floating on the water.

4. In an aeroplane flying machine of the biplane type; the combination with a central 105 framework having a front tubular upper spar and a front tubular lower spar, upper and lower right hand wings and upper and lower left hand wings, and hinged joints connecting the inner ends of the rear 110 spars of said right and left hand wings to said central framework to enable said right and left hand wings to be turned rearward from the flying position until they are about parallel with the central framework of the 115 machine; of projecting tapered pins fixed to the inner ends of the front upper and lower spars of the hinged wings, said pins being adapted to enter the ends of said tubular front upper and lower spars of said central

framework to guide said upper and lower front wing spars to engagement with said spars of said central framework, bolts to pass through the ends of said tubular front upper and lower spars of said central framework and through said tapered pins to secure said pins in position to hold said wings in their expanded and flying position, means for guiding said wing members near the 15 termination of their rearward folding movements and supporting said wing members upon the central framework at the completion of said folding movements, and a central stationary plane carried by said central framework to form a continuation of the 20 upper planes of the right and left hand wing members when in their expanded and flying position.

5. In an aeroplane flying machine of the 25 biplane type; the combination with a central framework having a front tubular upper spar and a front tubular lower spar, upper and lower right hand wings and upper and lower left hand wings, and hinged 30 joints connecting the inner ends of the rear spars of said right and left hand wings to said central framework to enable said right and left hand wings to be turned rearward from the flying position until they are 35 about parallel with the central framework of the machine; of means for guiding said folding wing members near the termination of their rearward movements and supporting same upon the central framework at the 40 completion thereof comprising an upper forked support located upon each side of the framework of the machine to receive vertical struts of the folding wing members, upper and lower flanged collars on said 45 struts to come above and below said upper forked supports, a lower forked support upon each side of said central framework said lower forked supports having their upper lateral extending surfaces downwardly inclined, and rollers on 50 said struts of said folding wing members to contact with said inclined surfaces of said lower forked supports to guide said folding wing members to bring said flanged collars above and below said upper forked supports on said central framework when said 55 wing members reach their folded positions.

7. In an aeroplane flying machine of the 60 biplane type; the combination with a central framework having a front tubular upper spar and a front tubular lower spar, upper and lower right hand wings and upper and lower left hand wings, and hinged 65 joints connecting the inner ends of the rear spars of said right and left hand wings to said central framework when the wing members reach their folded positions, and means for guiding to engagement and connecting the 70 ends of the front spars of said folding wing members to the central framework when in their expanded and flying positions.

8. In an aeroplane flying machine of the 75 biplane type; the combination with a central framework having a front tubular upper spar and a front tubular lower spar, upper and lower right hand wings and upper and lower left hand wings, and hinged 80 joints connecting the inner ends of the rear spars of said right and left hand wings to 85 said central framework to enable said right and left hand wings to be turned rearward from the flying position until they are about parallel with the central framework of the machine; of projecting tapered pins fixed to the inner ends of the front upper and lower spars of the hinged wings said pins being adapted to enter the ends of said tubular front upper and lower spars of said central framework to guide said upper and lower front wing spars to engagement with said spars of said central framework, bolts to pass through the ends of said tubular front upper and lower spars of said central framework and through said tapered pins to secure the latter in position, means for guiding said wing 90 members near the termination of their rearward movements and supporting same upon the central framework at the completion thereof comprising an upper forked support located upon each side of the framework of the machine to receive vertical struts of the folding wing members, upper and lower flanged collars on said struts to come above and below said upper forked supports, a lower forked support upon each side of said central framework said lower forked supports having their upper lateral extending surfaces downwardly inclined, and rollers on 95 said struts of said folding wing members to contact with said inclined surfaces of said lower forked supports to guide said folding wing members to bring said flanged collars above and below said upper forked supports on said central framework when said wing members reach their folded positions.

10. In an aeroplane flying machine of the 100 biplane type; the combination with a central framework having a front tubular upper spar and a front tubular lower spar, upper and lower right hand wings and upper and lower left hand wings, and hinged 105 joints connecting the inner ends of the rear spars of said right and left hand wings to said central framework to enable said right and left hand wings to be turned rearward from the flying position until they are about parallel with the central framework of the machine; of projecting tapered pins fixed to the inner ends of the front upper and lower spars of the hinged wings said pins being adapted to enter the ends of said tubular front upper and lower spars of said central framework, downwardly curved 110 guides at the ends of the front tubular lower spar of said central framework to guide said tapered pins into the ends of said front tubular lower spar, bolts to pass through the ends of said tubular front upper and lower spars of said central framework and through said tapered pins to secure the latter in position, means for guiding said wing 115 members near the termination of their rearward movements and supporting same upon the central framework at the completion thereof comprising an upper forked support located upon each side of the framework of the machine to receive vertical struts of the folding wing members, upper and lower flanged collars on said struts to come above and below said upper forked supports, a lower forked support upon each side of said central framework said lower forked supports having their upper lateral extending surfaces downwardly inclined, and rollers on 120 said struts of said folding wing members to contact with said inclined surfaces of said lower forked supports to guide said folding wing members to bring said flanged collars above and below said upper forked supports on said central framework when said wing members reach their folded positions.

members near the termination of their rearward folding movements and supporting said wing members upon the central framework at the completion of said folding movements, and a central stationary plane carried by said central framework to form a continuation of the upper planes of the right and left hand wing members when in their expanded and flying positions.

In witness whereof we have hereunto set 10
our hands in the presence of two witnesses.
